UNITED STATES PATENT OFFICE.

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

RAILWAY DRAFT APPLIANCE.

Application filed June 29, 1926. Serial No. 119,394.

My invention relates to railway draft appliances, and more particularly to locomotive and tender couplers in which a car coupler is pivotally connected to a pocket casting or bracket mounted upon the railway vehicle. It is to be understood, however, that the invention is not limited in its application to couplers of the locomotive and tender type.

10 The primary object of the invention is to provide a draft appliance of the type indicated in which efficient means for pivotally mounting the car coupler are associated with means for adjusting the height thereof.

15 The principal feature of the invention, generally stated, consists in respectively providing a coupler pocket and a car coupler with a plurality of spaced pivot lugs which overlap in alternating relation and through

20 which a pivot pin extends, adjacent lugs on each of the pivotally connected members being spaced apart a distance permitting a co-operating pivot lug and an adjusting shim to intervene therebetween.

25 Other features relating to advantageous relations of parts and details of construction will hereinafter appear.

In the drawings illustrating the invention, the scope whereof is pointed out in the 30 claims:—

Figure 1 is a plan view of a draft appliance embodying a preferred form of construction.

Figure 2 is a view, partly in elevation and 35 partly in vertical section, of the construction shown in Fig. 1, a portion of the coupler head being omitted.

Figure 3 is a detail perspective view of 40 one of the pivot pin bushings employed in the construction shown in Fig. 2.

Figure 4 is a view corresponding to Fig. 2 but illustrating the use of a different form 45 of pivot pin bushing.

Figure 5 is a detail perspective view of one of the bushings shown in Fig. 4.

In the drawings the member to which the car coupler 1 is pivotally connected by means 50 of the pivot pin 2 is a bracket member or coupler pocket 3 which is adapted to be secured to a locomotive or tender. The pocket member is integrally provided with a plurality of forwardly extending pivot lugs 4, 5, and 6, respectively, spaced vertically from each other. The lowermost of these lugs is

preferably extended forwardly substantially 55 beyond the others so as to constitute a floor or shelf 7 for preventing sagging or drooping of the coupler 1. The pivot lugs 4, 5 and 6 are tied together at the sides by the forwardly diverging lateral walls of the coupler 60 pocket 3, as indicated at 8 and 9, the divergence or flaring of said webs or walls being such as to permit the coupler to have the desired range of lateral swinging movement.

The rear end of the shank of the coupler 65 is recessed or slotted to provide a plurality of spaced pivot lugs 10 whose end faces are rounded, as indicated at 11, to conform to the curved cylindrical surfaces 12 of the coupler pocket. The space between the lugs 10 of the 70 coupler shank receives the intermediate pivot lug 5 of the pocket casting together with one or more shims 13. Similarly the adjacent pivot lugs 4 and 5 of the coupler pocket embrace the upper pivot lug 10 and 75 the shims 13, while the adjacent pivot lugs 5 and 6 receive between them the lower lug 10 of the coupler shank and a plurality of shims 14, the latter preferably being extended forwardly so as to be substantially 80 coextensive with the floor or coupler supporting shelf 7 of the pocket casting.

The pivot pin apertures in the lugs 10 of the coupler are preferably provided with cylindrical bushings 15 which encircle the 85 pivot pin 2, the upper ends of said bushings being formed with shouldered collars or flanges 16 which, by being received in correspondingly adjacent pivot lugs, prevent the bushings 90 from turning and thereby relieve the lugs from wear due to pivotal movements of the coupler. For the same purpose the lugs 4, 5 and 6 of the coupler pocket 3 have similar shouldered pivot pin bushings 17, 18 and 19, 95 respectively, associated therewith, the bushing 17 for the uppermost pivot lug preferably being formed on opposite sides with forwardly extending projections 20 engaging the correspondingly flattened faces 21 of the 100 head of the pivot pin, thereby preventing rotation of the latter. As there is no relative rotation of the pivot pin with respect to the shims 13 and 14, no bushings are provided for the pivot pin openings of the 105 shims. A cotter pin 22 extending through the lower end of the pivot pin may advantageously be employed as a simple means for

maintaining the latter in assembled position.

In the modified form of construction illustrated in Fig. 4 the bushings 23, 24 and 25 of the coupler pocket 26, as well as the bushings 27 and 28, are rectangular in exterior configuration for their full height, instead of merely being provided with a rectangular flange or collar at one end only. The openings in the respective pivot lugs for receiving these bushings are, of course, formed to correspond to the bushings. The construction shown in Fig. 4 being otherwise the same as that heretofore described, corresponding details of construction have been indicated by like reference numerals.

As illustrated in the drawings the coupler is at the highest point of adjustment relative to the pocket casting, but its position in this regard may be altered by changing the relation of the supporting shims. Upon being removed the long shims at the bottom of the pocket could not, of course, be inserted above the lower pivot lug of the coupler, and therefore additional shorter shims are to be employed as may be necessary to effect the desired change in the height of the coupler.

It will be perceived that the relation of parts enables adjustment of the height of the coupler to be easily effected while also permitting the pivot pin to act in quadruple shear.

I claim:—

1. In a draft appliance, the combination of a coupler pocket and a car coupler each provided with a plurality of spaced pivot lugs, a pivot pin extending through said lugs, said lugs being in overlapped relation and those on the pocket alternating with those on the car coupler, adjacent lugs on

the coupler pocket and adjacent lugs on the car coupler being spaced to permit the reception of one of said pivot lugs together with a shim, and a plurality of shims respectively positioned in the spaces between said adjacent lugs. 45

2. In a draft appliance, the combination with a member having a plurality of spaced pivot lugs, of a car coupler having a plurality of spaced pivot lugs, said lugs being in overlapping relation and those first named alternating with those of the car coupler, a pin extending through said several lugs for pivotally connecting the car coupler to said member, and a plurality of shims, said shims being respectively positioned in the space between adjacent pivot lugs of the coupler and in the space between the pivot lug of the coupler and one of the pivot lugs first named. 50

3. In a draft appliance, the combination 60 of a coupler pocket and a car coupler each provided with a plurality of spaced pivot lugs, a pivot pin extending through said lugs, the lugs being in overlapped relation and those on the pocket alternating with those 65 on the coupler, adjacent lugs on the coupler pocket and adjacent lugs on the coupler being spaced to receive one of said pivot lugs together with a shim perforated to receive said pivot pin, a plurality of shims respectively 70 positioned in the spaces between adjacent lugs of the coupler pocket and coupler, and a plurality of bushings interposed between said pivot pin and the coupler, each bushing respectively extending into the opening of a corresponding pivot lug of the coupler but not extending through the adjacent shim. 75

In testimony whereof I affix my signature.

ENOCH GEORGE, JR.
